UNITED STATES PATENT OFFICE

PAUL F. KRENZKE, OF CHICAGO, ILLINOIS

OVEN CONVEYER

Application filed June 20, 1929. Serial No. 372,868.

The present invention relates generally to conveyers for carrying unfinished articles through ovens, or like heating apparatus, for drying or baking purposes. More particularly the invention relates to that type of oven conveyer which comprises a pair of endless chains that are arranged in side-by-side relation and are supported by sprocket wheels so that parts thereof travel through the conveyer, cross-rods between the chains, and baskets or receptacles which are pivotally connected to and depend from the cross-rods and serve to support the articles and carry them through the oven during drive of the chain.

In ovens of the above mentioned type it has heretofore been customary to support the parts of the chains between the driving and idler sprocket wheels by means of flanged wheels which are journalled on the ends of the cross-rods and are adapted to travel on stationarily mounted track-sections. These wheels have proved in practice to be inefficient from an operating standpoint due to the fact that the grease or other lubricant which must necessarily be supplied thereto is reduced to carbon when subjected to the heat of the oven and, as a result, it loses its lubricating properties and causes the wheels to bind on the cross-rods.

One object of the invention is to provide a conveyer of the character under consideration in which the parts of the chains between the driving and idler sprocket wheels are supported by units which are of an improved character and have decided advantages over the flanged wheels heretofore used in that they require no lubricant, offer a minimum frictional retardation to the movement of the chains, and are not affected by contraction and expansion thereof due to the differential temperatures that exist inside and outside the oven. In general, it may be stated that each of these units consists of a shoe which is fixedly secured to one of the ends of a cross-rod, and a series of rollers which are revolvable around the shoe and travel on stationary track sections between the various sprocket wheels.

Another object of the invention is to pro-

vide an oven conveyer embodying chain-supporting units of the aforementioned type, in which means of an improved character is provided for preventing lateral displacement of the series of rollers relatively to the 55 shoes.

A further object of the invention is the provision of improved means whereby the ends of the cross-rods are connected to the 60 shoes of the supporting units and the chain.

A still further object of the invention is to provide an oven conveyer which is generally of new and improved construction, may be manufactured at a comparatively low cost, 65 and is more efficient in operation than previously designed conveyers for the same purpose.

Other objects of the invention and the various advantages and characteristics of the 70 present conveyer construction will be apparent from a consideration of the following detailed description.

The invention consists in the several novel features which are hereinafter set forth and are more particularly defined by the claims 75 at the conclusion hereof.

In the drawings which accompany and 80 form a part of this specification or disclosure and in which like numerals of reference denote corresponding parts throughout the several views:

Figure 1 is a vertical longitudinal sectional view of an oven conveyer embodying the invention;

Figure 2 is a transverse section taken on 85 the line 2—2 of Figure 1;

Figure 3 is a view, partly in side elevation and partly in section of one of the units for supporting the parts of the chains that are disposed intermediately of the sprocket wheels;

Figure 4 is a plan view of the unit that is disclosed in Figure 3;

Figure 5 is a section taken on the line 5—5 95 of Figure 3 and illustrating the manner in which the ends of the cross rods are secured to the chain-supporting units and the chain; and

Figure 6 is a detail view of the link ar- 100

angement which is used in connection with the supporting-unit rollers.

The conveyer which forms the subject matter of the present invention is adapted primarily for use in carrying through a heating apparatus or oven O articles that are to be heated or baked. The oven is illustrated more or less diagrammatically in Figures 1 and 2 of the drawings and is shown, by way of example, as comprising a tubular horizontally extending casing o' which is heated by burners o². The latter extend transversely across the bottom portion of the casing and are of the type that is supplied with gas. The conveyer embodies a pair of endless chains 10 which travel in vertical planes and are positioned in side-by-side relation. Pairs of sprocket wheels 11 operate to support the chains 10 and are so arranged that the upper reaches of the chains pass longitudinally through the oven O. The lower reaches of the chains pass beneath the oven inasmuch as the chains are adapted to travel, as previously pointed out, in vertical planes. Cross- rods 12 extend between and are supported by the chains 10. Pivots connected to and depending from these rods are baskets or receptacles 13 which are adapted to receive the articles to be heated and carry such articles through the oven O. The receptacles are provided with straps or hangers 14 which serve as the pivotal connections between the cross-rods 12 and said receptacles. Collars 15 are fixedly secured to the cross-rods and abut against the straps 14 to prevent lateral displacement of the receptacles relatively to the chains 10. The sprocket wheels 11 which support the chains 10 are individually mounted on stub shafts 16 so that the space beneath the rods 12 and between the chains 10 is free or unobstructed and permits of the ready passage or travel of the receptacles 13. The stub shafts 16 are journalled in brackets 17 which are secured to uprights or standards 18. The latter are rigidly held in place at the sides of the chains and serve to sustain the oven O. The chains 10 are driven to effect movement of the receptacles through the oven, by means of gear wheels 19 which are keyed or otherwise rigidly secured to the stub shafts 16 of one pair of sprocket wheels 11. The gear wheels 19 are adapted to be driven conjointly and in such a manner as to cause the chains and receptacles to move slowly through the oven.

Each of the chains 10 consists of solid prism-like links 20 and pairs of link-bars 21. These links and pairs of link-bars alternate with one another and are pivotally connected together by pivot pins 22. The latter extend through holes 23 and 24 which are punched or otherwise formed in the ends of the links and link-bars respectively. The ends of the pins 22 project outwardly of the outer faces of the link-bars 21 and are riveted over or

provided with cotter pins or similar retaining devices in order to hold the link-bars in place and in connected relation with respect to the links 20. The pivot pins constitute the articulation points for the links and the link-bars and are positioned, by virtue of the arrangement of the sprocket wheels 11, so that the pins of one chain are co-axial or in longitudinal alignment with the pins of the other chain. The cross-rods 12 are hollow and are connected to the chains 10 by studs 25 which project laterally and inwardly with respect to said chains. These studs are formed as integral parts of some of the links 20 and extend into the ends of the cross-rods 12. Said cross-rods are secured in place around the studs by bolts 26 which extend transversely through diametrically opposite holes 27 in the ends of the cross-rods and through holes 28 in the distal ends of the studs. The bolts 26, by extending in the manner set forth, operate to secure the cross-rods and studs together against relative axial and rotative movement. The cross-rods 12 are connected to the chains 10 at such intervals that the receptacles do not interfere with one another during travel thereof either in the horizontal or the vertical reaches of the chains. Said chains are supported intermediate the sprocket wheels 11 by means of units 29 which are secured to the ends of the cross-rods 12 and cooperate with stationary track-sections 30. The latter extend between the sprocket wheels 11 and are positioned slightly inwardly of the chains 10. Supporting-members 31 which are secured to the uprights or standards 18 serve to support fixedly the track-sections in their operative position.

Each of the units 29 comprises an elongated shoe 32 and an endless series of rollers 33. The rollers are adapted to contact with the track-sections 30 and are revolvable about the shoe 32 as hereinafter described. Said shoe is preferably made of a one-piece casting and consists of a hub 34, a web 35 and a rim 36. The hub projects laterally from both faces of the web and is provided with a bore 37 for receiving the end of the cross-rod with which the shoe is associated. The rim 36, like the hub 34, projects laterally from both faces of the web 32. The end parts of the rim 36 are semi-circular in conformation. The parts of the rim between said end parts are substantially parallel and are adapted to be brought into parallel relation with respect to the head parts 30^a of the track-sections 30. The rim 36 corresponds substantially in width to said head parts 30^a of the track-sections. The rollers 33 are connected together in series form and so that they are conjointly movably around the rim 36, by means of a link arrangement consisting of pairs of inner link-bars 38 and pairs of outer link-bars 39. These various pairs of link-bars

alternate with one another and are pivotally connected together by pins 40. The latter are provided at the ends thereof with externally threaded stems 41 which extend through 5 circular holes 42 in the ends of the outer link-bars 39 and are provided with nuts 43 which operate to clamp said outer link-bars against the end parts of the pins. The ends of the inner link-bars 38 are provided with circular holes 44 through which extend the pins 40. The rollers 33 are rotatably mounted on the pins 40 and are positioned between the contiguous or adjoining ends of the link-bars 38 and 39. Said rollers are provided with cylindrical holes 45 through which the pins 40 extend. The openings 44 and 45 are preferably formed so that the diameter thereof is slightly larger than that of the pins 40. As a result of this arrangement, the inner link-bars and the rollers are loosely mounted on the pins 40 and consequently need no lubricant and will not bind on the pins when they expand or contract in response to temperature changes. An additional characteristic of 15 having the rollers and inner link-bars mounted loosely on the pins 40 is that the series of rollers is sufficiently free to permit the same to revolve around the rim of the shoe readily and without offering undue frictional 20 retardation to the drive of the chains. Every other roller 33 is provided at the ends thereof with radially extending flanges 46 which lap the rim 36 and are adapted to straddle the contiguous part of the adjoining track-sections 25 for the purpose of preventing transverse displacement of the rollers with respect to the shoe 32. A further function of the flanges 46 is to prevent the shoe from being displaced laterally relatively to the track-sections. The shoe 32 is secured in place by the 30 bolt 26 that is associated with the adjoining cross-rod. Said bolt is of such length that the ends thereof pass through aligned holes 34^a in the inner part of the collar 34. A characteristic and an advantage of having the bolt 35 26 extend both through the cross-bar and the collar is that but one securing instrumentality is necessary to connect rigidly the shoe and cross-rod to the stud 25. The holes 34^a are so arranged with respect to the bolt 26 that the 40 shoe 32 extends in substantially parallel relation with respect to the adjacent link 20. To prevent the series of rollers and the link arrangement that is associated therewith 45 from sagging when the shoe passes around the sprocket wheels and out of alignment with the track-sections, an oval shaped guide-member 47 is provided. This member is preferably formed of angle iron and embodies an outwardly extending leg 48 which overlaps the inner ends of the rollers 33, as illustrated in Figure 5. U-shaped brackets 49 serve to support the guide-member in its operative 50 position. These brackets are connected by

bolts 50 to the web 35 and the other or vertical leg of the guide-member 47.

The operation of the conveyer will be as follows: When the gear wheels 19 are driven, the chains 10 are caused to move around the sprocket wheels 11 and, as a result, effect movement of the receptacles 14 through the oven O. During this drive movement of the conveyer, the portions of the chains that are between the sprocket wheels are supported by the units 29 which operate in conjunction with the track-sections 30. When the units are moved the series of rollers 33 travel in rotative succession on the track-sections and revolve about the shoes 32. As the units 29 pass out of alignment with the track-sections and around with the sprocket wheels 11, the series of rollers 33 are prevented by the guide-member 47 from sagging and being displaced laterally. When the series of rollers 33 are revolved about the shoes 32 by virtue of their contact with the track-sections, the radially extending flanges 46 at the ends of the rollers straddle the track-sections and the rims 36 of the shoes in such a manner that the parts of the chains that are disposed between the sprocket wheels are held against transverse displacement. Inasmuch as the series of rollers around the shoes 32 need no lubricant, binding is eliminated during travel of the units through the oven O.

The oven conveyer herein disclosed may be manufactured at a comparatively low cost and is efficient from an operating standpoint in that no lubricant is needed for the rollers which are used in connection therewith.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a conveyer, the combination of a pair of endless chains arranged in side-by-side relation, sprocket wheels for supporting and driving the chains, track-sections between the sprocket wheels, cross-rods positioned between and having the ends thereof connected to the chains, and units for supporting the parts of the chains that are disposed intermediately with respect to the sprocket wheels, comprising shoes on the ends of the rods and series of rollers travelable on the track-sections and revolvable about the shoes.

2. In a conveyer, the combination of a pair of endless chains arranged in side-by-side relation, sprocket wheels for supporting and driving the chains, track-sections between the sprocket wheels, cross-rods positioned between and having the ends thereof connected to the chains, and units for supporting the parts of the chains that are disposed intermediately with respect to the sprocket wheels,

comprising shoes on the ends of the rods and series of rollers travelable on the track-sections and revolvable about the shoes, the rollers of each series being connected together by links for conjoint movement.

3. In a conveyer, the combination of a pair of endless chains arranged in side-by-side relation, sprocket wheels for supporting and driving the chains, track-sections between the sprocket wheels, cross-rods positioned between and having the ends thereof connected to the chains, and units for supporting the parts of the chains that are disposed intermediately with respect to the sprocket wheels,

15 comprising shoes on the ends of the rods and series of rollers travelable on the track-sections and revolvable about the shoes, some of the rollers being provided with radially extending flanges at the ends thereof operative to straddle the shoes and the track-sections for the purpose of preventing sidewise displacement of the rods and chains relatively to the track-sections and of the series of rollers relatively to the shoes.

20 4. In a conveyer, the combination of a pair of endless chains arranged in side-by-side relation, sprocket wheels for supporting and driving the chains, track-sections between the sprocket wheels, cross-rods positioned be-

25 tween and having the ends thereof connected to the chains, and units for supporting the parts of the chains that are disposed intermediately with respect to the sprocket wheels, comprising shoes on the ends of the rods,

30 series of rollers travelable on the track-sections and revolvable about the shoes, and guide-members secured to the shoes and operative to prevent displacement of the rollers when the units are out of engagement with

35 the track-sections and move about the sprocket wheels.

40 5. In a conveyer, the combination of a pair of endless chains arranged in side-by-side relation and provided with pairs of inwardly extending studs, sprocket wheels for supporting and driving the chains, track-sections between the sprocket wheels, hollow cross-rods disposed between and having the ends thereof connected to the studs, and units for sup-

45 porting the chains intermediately of the sprocket wheels, comprising shoes on the ends of the rods and series of rollers travelable on the track-sections and revolvable about the shoes.

50 6. In a conveyer, the combination of a pair of endless chains arranged in side-by-side relation and provided with pairs of inwardly extending studs, sprocket wheels for supporting and driving the chains, track-sections between the sprocket wheels, hollow cross-rods disposed between the chains and having the

55 ends thereof fitting around the studs, and units for supporting the chains intermediately of the sprocket wheels, comprising shoes on the ends of the rods and series of rollers

travelable on the track-sections and revolvable about the shoes.

7. In a conveyer, the combination of a pair of endless chains arranged in side-by-side relation and provided with inwardly extending pairs of studs, sprocket wheels for supporting and driving the chains, track-sections between the sprocket wheels, hollow cross-rods extending transversely between the chains and having the ends thereof fitting around the studs, units for supporting the chains intermediately of the sprocket wheels, comprising shoes on the ends of the rods and series of rollers travelable on the track-sections and revolvable about the shoes, and means for rigidly connecting together the studs, shoes and ends of the cross-rods.

75 8. In a conveyer, the combination of a chain, sprocket wheels for supporting and driving the chain, a track-section between the sprocket wheels, and units for supporting the portion of the chain that is disposed intermediately with respect to said sprocket wheels, comprising shoes connected to the chain and movable therewith and series of rollers travelable on the track-section and revolvable about the shoes.

80 9. In a conveyer, the combination of an endless chain, sprocket wheels for supporting and driving the chain, track-sections between the sprocket wheels, and units for supporting the parts of the chain that are disposed intermediately with respect to said sprocket wheels, comprising shoes connected to the chain and movable therewith, and series of rollers travelable on the track-sections and revolvable about the shoes, the rollers of each series being connected together by links for conjoint movement.

85 10. A roller unit for use in connection with a conveyer, comprising a shoe adapted to be connected to an elongated element and to be shifted by said element over and longitudinally of a track-section, an endless series of link-connected rollers disposed around the periphery of the shoe, travelable on the track-section and revolvable about the shoe, and means for preventing axial displacement of the rollers relatively to said shoe.

90 11. A roller unit for use in connection with a conveyer, comprising a shoe adapted to be connected to an elongated element and to be shifted by said element over and longitudinally of a track-section, an endless series of link-connected rollers disposed around the periphery of the shoe, travelable on the track-section and revolvable about the shoe, and flanges on the ends of some of the rollers for lapping the sides of the shoe and preventing axial displacement of the rollers with respect to said shoe.

Signed at Chicago, Illinois, this 15th day of June, 1929.

PAUL F. KRENZKE.
